UNITED STATES PATENT OFFICE.

WILLIAM F. LYNCH, OF BLOOMFIELD, NEW JERSEY, ASSIGNOR TO PEERLESS TUBE CO., OF BLOOMFIELD, NEW JERSEY, A CORPORATION OF NEW JERSEY.

FEEDING MECHANISM.

Application filed September 14, 1926. Serial No. 135,468.

This invention relates to feeding mechanism especially designed for use in connection with machines for operating upon slugs of material and comprehends a mechanism 5 for feeding slugs by gravity in a column, which mechanism includes automatic means for righting or ejecting misplaced slugs in the column so as to insure the delivery of the same in a predetermined or proper position.

The invention furthermore comprehends in a machine for operating upon slugs of material, a substantially vertical feed element through which the majority of the 15 slugs gravitationally feed in a predetermined position, together with means operable by a moving part of the machine for ejecting therefrom or righting certain of the slugs which are fed out of said desirable or 20 predetermined position.

As a further object the invention comprehends a feeding mechanism of the character set forth which is extremely simple in its construction and mode of operation, which 25 is inexpensive to manufacture and install upon the machine with which it is used, and which is thoroughly reliable and highly efficient in its purpose.

With the above recited and other objects 30 in view, reference is had to the following specification and accompanying drawings in which there is exhibited one example or embodiment of the invention which is in no way intended as a limitation upon the scope 35 of the appended claims as it is to be clearly understood that variations and modifications which properly fall within the scope of said claims may be resorted to when found expedient.

40 In the drawings—

Figure 1 is a vertical sectional view through a machine equipped with the improved feeding mechanism;

Fig. 2 is a sectional view taken approximately on the line 2—2 of Fig. 1;

Fig. 3 is an enlarged detail sectional view through the righting and ejecting means;

Fig. 4 is a fragmentary sectional view taken approximately on the line 4—4 of Fig. 3.

Referring to the drawings by characters of reference, A designates generally a machine for operating upon slugs of material, which includes movable and stationary 55 punch die elements B and C, the former be-

ing carried and actuated by the punch gate D, which in turn is driven from a crank shaft E by a pitman F.

The feeding mechanism constituting the present invention consists of a hopper 10, 60 which is preferably mounted upon punch gate D for vertical movement therewith, and which is adapted to contain a supply of slugs G. A vertical feed element or tube 11 is mounted by a suitable clamping device 12 upon a stationary part H of the machine, with its upper end extending through the bottom of the hopper and its lower end disposed in slightly spaced relation above the bed plate I of the machine, 70 the said upper end being so positioned that upon vertical movement of the hopper the slugs are induced to feed into the upper end of the tube or element 11 and to gravitate therethrough in stack or column formation. 75

In practice, it has been found that the great majority or a large percentage of the slugs fall in a desirable predetermined position as illustrated, while the remainder assume various positions illustrated at G¹ and 80 G² in Fig. 3.

In order to provide means for either righting or ejecting the misplaced slugs illustrated at G¹ and G², the tube or guide 11 intermediate its ends is formed with diametrical- 85 ly opposed slots or openings 13 and 14. Mounted upon the bed plate I of the machine is the usual finger feed slide J and feed finger K carried thereby which is reciprocated by a bell crank motion L imparted thereto by a suitable rod M from the crank shaft E of the machine. Mounted upon the finger feed slide J, is an upstanding bracket 15, in the upper end of which a bearing sleeve 16 is arranged. The bearing sleeve 90 has mounted therein for sliding movement, a tine 17 having a pointed outer extremity or terminal 18 and a reduced shank 19 at its inner end which forms a shoulder 20 at its juncture with the main body of the tine. An 100 adjustable abutment element 21 is attached at the inner end of the bearing sleeve 16 and between said abutment and the shoulder 20 a coiled expansion spring 22 is disposed which surrounds the shank 19. 105

In operation, as the finger feed slide reciprocaters, the tine moving therewith is projected through the openings 13. If the pointed extremity or terminal 18 thereof engages with the slugs G, which are in the 110

desirable predetermined position, the movement of the tine is arrested while the sleeve 16 continues to move, compressing or contracting the spring 22. If, however, the 5 pointed terminal or extremity 18 encounters a slug in the position illustrated at G¹, the slug will be righted or turned to the desirable predetermined position to the remainder of the stack. If the terminal 18 of the tine 10 encounters a slug in the position illustrated at G², it is obvious that the said slug will be ejected from the guide element or tube 11 through the opening 14. Under this arrangement, it is obvious that a feed mechanism 15 has been devised which insures the delivery of the slugs G in the desirable predetermined or proper position for feeding to the die elements B and C by a feed finger K.

What is claimed is:

20 1. A device for feeding slugs by gravity in a column, and automatic means for righting mispositioned slugs in the column or ejecting said mispositioned slugs therefrom.

25 2. In a machine for operating upon slugs of material, a substantially vertical feed element through which the majority of the slugs gravitationally feed in a usual or predetermined position, and means operable by a moving part of the machine for ejecting 30 slugs therefrom or righting certain of the slugs which are disposed out of said usual or predetermined position.

35 3. In a machine for operating upon slugs of material, a substantially vertical tubular feed element through which the majority of the slugs gravitationally feed in a usual or predetermined position, and means operable by a moving part of the machine for ejecting 40 slugs which are disposed out of said usual or predetermined position.

45 4. The combination with a machine for operating upon slugs fed by gravity in a stack or column, of mechanism for insuring delivery thereof in a predetermined position to the operating elements of the machine, said mechanism including means for righting or ejecting certain of the slugs which are disposed out of said predetermined position.

50 5. The combination with a machine for operating upon slugs fed by gravity in a

stack or column, of mechanism for insuring delivery thereof in a predetermined position to the operating elements of the machine, said mechanism including means for righting or ejecting certain of the slugs which are disposed out of said predetermined position, the righting or ejecting means consisting of a spring-pressed yieldable tine tensioned by said spring, yieldable when engaging the slugs arranged in the predetermined position and tensioned by said spring against yielding when engaging the misplaced slugs, whereby to effect their righting or ejection.

6. The combination with a machine for operating upon slugs, of a mechanism for automatically feeding the slugs in proper position to the slug-operating means of the machine, said mechanism comprising a slug 70 hopper and a vertical feed tube extending into the hopper, said hopper and feed tube mounted for relative vertical movements whereby the slugs are gravitationally fed through the feed tube, said feed tube having 75 diametrically disposed openings extending longitudinally thereof, and a device movable through one of the openings for ejecting through the other opening certain of the slugs disposed in a wrong position and for turning other of the slugs from a wrong to a righted position.

7. The combination with a machine for operating upon slugs, of a mechanism for automatically feeding the slugs in proper 85 position to the slug-operating means of the machine, said mechanism comprising a slug hopper and a vertical feed tube extending into the hopper, said hopper and feed tube mounted for relative vertical movements 90 whereby the slugs are gravitationally fed through the feed tube, said feed tube having diametrically disposed openings extending longitudinally thereof and a device movable through one of the openings for ejecting 95 through the other opening certain of the slugs disposed in a wrong position and for turning other of the slugs from a wrong to a righted position, said device including tensioned means yieldable when engaging slugs 100 disposed in the proper position.

WILLIAM F. LYNCH.
